United States Patent Office

Des. 210,511

Patented Mar. 19, 1968

210,511

BOOT

William J. Dorsey, Newark, N.J., assignor to Kaysam Corporation of America, Paterson, N.J., a corporation of New Jersey

Filed Nov. 16, 1966, Ser. No. 4,700

Term of patent 14 years

(Cl. D2—272)

Fig. 2.

Fig. 1.

Fig. 3.

FIG. 1 is a side perspective view of a boot showing my new design;

FIG. 2 is a side perspective view of the side opposite thereto; and

FIG. 3 is a side perspective view of the boot as it appears with the cuff in a turned up position.

I claim:

The ornamental design for a boot, as shown.
